TRENCH FILLING AND SHOULDER SPREADING MACHINE

Raymore D. MacDonald, Eureka, Ill., assignor to Ulrich Manufacturing Co., Roanoke, Ill., a corporation of Delaware

Filed Apr. 25, 1958, Ser. No. 730,943
16 Claims. (Cl. 94—46)

The present invention relates to that class of road construction machines commonly known as trench filling and shoulder spreading machines, which are frequently employed in road widening operations. In these road widening operations, it is a conventional practice to first cut a longitudinal trench out of the soil along one side edge or margin of an existing road composed of concrete, macadam or other road material, following which this trench is filled with bituminous mix, crushed stone, gravel, concrete or other desired filling material, such filling operation being performed by a trench filling machine. The width of the fill is dependent upon the extent to which it is desired to widen the road, and the depth of the fill is dependent upon the depth of road bed desired, the filling material used, whether the new fill and the existing road is to be resurfaced, etc.

Road construction machines of this general type are also employed in shoulder work in which a widened shoulder is spread along the side edge of an existing road by spreading bituminous mix, crushed stone, etc. along this side edge. In this regard, the present machine herein disclosed is not limited in use to trench filling operations, but is also capable of shoulder work in which a widened shoulder is spread along the edge of an existing road by spreading black top, crushed stone, etc. to a controlled depth, slope or grade.

One of the principal objects of the invention is to provide an improved trench filling and shoulder spreading machine which is constructed in the form of an attachment unit for quick and easy attachment to and detachment from a conventional motor grader. The conventional motor grader thus serves as the prime mover or power vehicle for propelling my improved attachment unit along the roadway in the trench filling or shoulder spreading operation. Considering the range of equipment owned by the average road building contractor or road maintenance contractor, the conventional motor grader is generally the primary motorized vehicle, or is one of the most prevalent pieces of equipment in the entire road working field. Thus, by constructing my improved machine for attachment to a motor grader, I avoid the much greater initial cost and maintenance cost of a completely self-propelled machine; and I also obtain increased productive capacity and other operating advantages which stem from the use with the motor grader.

For example, the strike-off blade action of the attachment unit sets up a very large diagonally acting side draft, but the relatively long wheel base of the motor grader and its great resistance to side draft effectively resists this side draft set up in the strike-off blade of the attachment unit.

According to the improved coupling arrangement herein disclosed, my improved attachment unit is coupled up to the front end of the motor grader to be pushed ahead of the grader. The attachment unit has a hopper at its front end which receives the fill material from successive dump trucks which move into dumping position ahead of the attachment unit and dump their material from the rear ends of their dumping bodies into the hopper. In order that the operation of dumping the material from the dump body of the truck into the hopper of the attachment unit can be effected without stopping the forward motion of the attachment unit it is usually

2

necessary to maintain pushing contact between the attachment unit and each dumping truck, whereby the attachment unit pushes the dumping truck ahead of it. The relatively large traction power available from the motor grader affords sufficient power to push the largest size of dump truck ahead of the attachment unit in the truck dumping operation, even up the steepest grades.

Another object of the invention is to provide an improved attachment unit adapted for attachment to a conventional motor grader wherein the strike-off blade of the unit is connected to be governed and controlled by the scraper blade of the conventional motor grader. As is well known, the scraper blade of the conventional motor grader is capable of a wide variety of positioning adjustments, such as: (1) raising and lowering of the scraper blade; (2) horizontal rotation of the blade around the vertical axis of the blade supporting circle; (3) lateral tilting of the blade by raising and lowering opposite sides of the circle; (4) side shifting of the blade and blade circle, etc. Most or all of these positioning adjustments of the scraper blade are performed by mechanical or hydraulic power in the later designs of motor graders, and the mounting and adjustments of the scraper blade are capable of withstanding the extremely large stresses which are encountered by the scraper blade in the ordinary performance of a grading operation by the motor grader. I make these various adjustments of the scraper blade and its sturdiness of mounting available to the strike-off blade of my attachment unit by connecting the outer end of the strike-off blade with the scraper blade, so that this outer end of the strike-off blade responds to adjustments given to the scraper blade of the grader. The inner end of the strike-off blade of my trench filling and shoulder spreading machine is preferably made responsive to a separate and independent control located on this filling and spreading machine, but, as above stated, the outer end of such strike-off blade is positively connected with and made responsive to the scraper blade of the grader. Thus, it will be seen that by making the outer end of the strike-off blade of my machine responsive to positioning adjustments of the scraper blade of the motor grader, I can effect all of the necessary power operated adjustments of the outer end of the strike-off blade, through the motor grader, without burdening the attachment unit with the substantial cost, complication and weight of providing such power operated adjustments on the attachment unit. Still further, as above intimated, I utilize the very large side draft resistance inherent in the motor grader to sustain the side draft set up in the outer end of the strike-off blade of my attachment machine. In this regard, the above described feature of pushing the attachment unit ahead of the motor grader constitutes a very important factor in being able to establish the desired adjusting and side draft transmitting connection between the scraper blade of the motor grader and the strike-off blade of the attachment unit, whereby the outer end of the strike-off blade is made responsive to controls effected through the scraper blade, and also has its side draft borne by the scraper blade.

Another object of the invention is to provide an improved three-point mounting or suspension of the attachment unit. These three points comprise two laterally spaced caster wheel sets at the front of the attachment unit, and a ball-and-socket mounting joint between the rear portion of the attachment unit and the front end of the motor grader. This three point mounting of the attachment unit, with the universal joint type of draft transmitting connection between the attachment unit and the motor grader, permits relative transverse rocking movement between the attachment unit and the motor grader, each independently of the other, as the two vehicles pass

over uneven road surfaces. A pivotally acting stabilizer brace extends between the motor grader and the attachment unit, preferably having a ball-and-socket connection at its front end with the attachment unit. This stabilizer brace compels the attachment unit to steer directly with the front end of the motor grader, and supplements the draft transmitting action of the ball-and-socket mounting joint, while still permitting the free transverse rocking movement between the attachment unit and motor grader. This free transverse rocking movement results in the strike-off blade being more accurately maintained at its predetermined set height of strike-off of the filling material, as will be later described. This free transverse rocking movement also avoids the transmission of twisting, racking stresses from the frame of the motor grader to the frame of the attachment unit, or vice versa.

Another object of the invention is to provide an improved lifting jack, preferably hydraulic in its operation, for manually lifting and lowering the rear end of the attachment unit in performing the manual operation of coupling and uncoupling the attachment unit and the motor grader at the ball-and-socket mounting joint.

The trench filling and shoulder spreading unit has a conveyor belt traveling in the bottom of the material receiving hopper of the unit for discharging this material along the side edge of the road; and another object of the invention is to provide improved regulating means for regulating the speed of travel of this conveyor belt through infinitely small speed changes. Thus, it is possible for the operator to regulate very closely the rate of discharge of the filling material to take care of different depths and widths of fill and different operating conditions.

Another object of the invention is to provide an improved hydraulically tilted dump apron or front hopper wall at the front edge of the material receiving hopper, which can be readily raised and lowered by the operator for the purpose of accommodating different body heights of different dump trucks, and also for the purpose of increasing the hopper capacity. This tilttable dump apron increases the capacity of the hopper by providing a front hopper wall which can be disposed substantially horizontally for receiving material during the truck dumping operation, and which can thereafter be tilted upwardly to discharge the material resting thereon rearwardly back to the conveyor belt.

Another object is to provide an improved design of hinged trench and curb seal which will prevent material from being carried from the trench back under the machine on to the pavement; and which can also be readily folded up out of the trench when the machine is in transport.

Further objects of the invention pertaining to the conveyor belt of the machine are to provide improved self-cleaning conveyor belt seals which are tapered so as to be self-relieving in the direction of travel; to provide an improved floating type of inside belt scraper at the tail pulley of the belt; and to provide an improved arrangement of clean-out holes in the sides of the conveyor belt channel.

Still another object is to provide the machine with an improved frame construction characterized by a transversely extending frame tube which functions firstly as the backbone of the frame; secondly it serves as an oil reservoir adapted to store a large quantity of oil for the hydraulic drive and control systems; and thirdly because of its large surface area it functions as a radiator to dissipate heat from the oil.

Other objects, features and advantages of the invention will appear from the following detail description of certain preferred embodiments thereof.

In the accompanying drawings illustrating such embodiments:

FIGURE 1A is a fragmentary plan view showing the front portion of a conventional motor grader and showing

the trench filling embodiment of my improved attachment unit coupled thereto, this trench filling embodiment being designated AU.

FIGURE 1B is a similar view showing the shoulder spreading embodiment of the attached front unit, coupled to the conventional motor grader, this shoulder spreading embodiment being designated AU'.

FIGURE 2 is a perspective view of the rear end of the attachment unit having the trench filling equipment mounted thereon, showing it uncoupled from the motor grader.

FIGURE 3 is a fragmentary rear elevational view of most of one of the attachment units, showing it uncoupled from the motor grader similarly to FIGURE 2.

FIGURE 4 is a fragmentary perspective view of the left hand portion of the trench filling embodiment of attachment unit AU, showing the front and left hand side thereof.

FIGURE 5 is a side elevational view of the trench filling embodiment AU, showing the strike-off box in its lowered position in a trench.

FIGURE 6 is a somewhat similar view of this same trench filling embodiment AU on a slightly smaller scale, with the strike-off box removed or broken away to illustrate more clearly the point of discharge of the fill material from the machine, this view also illustrating fragmentarily the rear end of a dump truck in the act of dumping fill material into the hopper.

FIGURE 6A is a view quite similar to FIGURE 6, but 30 of the shoulder spreading embodiment AU'.

FIGURE 7 is an isolated fragmentary plan view of the stabilizer bar which is connected between either of the two attachment units AU, AU', and the motor grader.

FIGURE 8 is a plan view of an improved floating type 35 of inside belt scraper used on either embodiment AU or AU', this view being on a larger scale.

FIGURE 9 is a fragmentary elevational view of my improved design of hinged trench and curb seal used on either embodiment.

FIGURE 10 is a transverse sectional view through the same, taken approximately on the plane of the line 10— 40 10 of FIGURE 9.

FIGURE 11 is a detail section taken on the plane of the line 11—11 of FIGURE 5.

FIGURE 12 is a fragmentary side elevational view of the intermediate portion of the conventional motor grader MG illustrated in FIGURES 1A and 1B, but on a larger scale, and FIGURE 13 is a fragmentary transverse sectional view taken on the plane of the line 13—13 of FIGURE 12, these two figures showing in greater detail certain of the conventional controls ordinarily utilized for effecting lifting, lowering and lateral shifting adjusting movements of the conventional scraper blade of such a grader, which adjusting movements are transmitted from such 50 scraper blade to the strike-off blade of the shoulder spreading attachment unit AU' of FIGURE 1A.

FIGURE 14 is a fragmentary elevational view of part 55 of said shoulder spreading attachment unit AU', corresponding to a section taken approximately on the plane of the line 14—14 of FIGURE 1A, showing the vertically moving hydraulically operated slide, together with the hinging articulation and pivoting articulation of the inner end of the strike-off blade of said shoulder spreading attachment unit AU'.

FIGURE 15 is a fragmentary plan view of FIGURE 14.

FIGURE 15A is a detail section of FIGURE 15.

FIGURE 16 is a fragmentary elevational view, corresponding to a view taken on the plane of the line 16—16 of FIGURE 1B, showing the extensible boom for connecting the scraper blade of the motor grader with the strike-off blade of the shoulder spreading attachment unit AU'.

FIGURE 17 is a fragmentary plan view of FIGURE 16.

FIGURE 18 is a fragmentary elevational view, corresponding to a view taken on the plane of the line 18—18

of FIGURE 1B, showing the margin defining plate and the shoe plate at the outer end of the strike-off blade.

FIGURE 19 is a plan view of FIGURE 18.

FIGURE 20 is a fragmentary detail view showing in vertical section the ball and socket transversely rockable mounting joint which couples the rear portion of the attachment unit to the front end of the motor grader, and;

FIGURE 21 is a transverse detail sectional view taken approximately on the plane of the line 21—21 of FIGURE 20.

In FIGURE 1A I have shown the trench filling embodiment of my attachment unit, designated AU in its entirety, and in FIGURE 1B I have shown the shoulder spreading embodiment of my attachment unit, designated AU' in its entirety. Both attachment units are quite similar up to the point of discharge of the fill material from the conveyor belt, following which the trench filling embodiment causes the fill material to fill a previously cut trench along the side of the road, whereas the shoulder spreading embodiment causes the fill material to be spread outwardly from the side of the road, usually over a substantial span, to build up the shoulder along side the road. Both attachment units are to be coupled to the front end of any conventional or standard motor grader, which is designated MG in its entirety. The attachment unit AU or AU' is adapted to receive its filling material from successive dump trucks which are pushed ahead of the attachment unit and which dump rearwardly into the material receiving hopper of the unit, the rear end of one of such dump trucks being indicated fragmentarily at DT in FIGURE 6.

Because of the close collaboration of the motor grader MG with each of the attachment units AU, AU' I shall first briefly describe the main parts of a conventional motor grader. It usually comprises a suitable frame structure 25 supported at its front end on front steering wheels 26 and at its rear end on rear driving wheels 27. The rear driving wheels are generally but not necessarily in tandem pairs. An internal combustion engine 29 operates to drive the rear driving wheels 27 and also the accessories, such as the oil pump of the hydraulic control system; and in the case of a six wheel drive motor grader this engine also serves to drive the front steering wheels 26. Located under the frame 25 between the front wheels 26 and rear wheels 27 is the conventional scraper blade 30 which is so mounted and connected with the frame 25 as to be capable of a wide variety of positioning adjustments. For example, the blade is mounted on a so-called "circle" 31 having a substantially vertical rotative axis which enables the scraper blade to be rotated in a substantially horizontal plane to different horizontal angles under the frame 25. The horizontal rotation of the blade around the axis of the circle 31 is usually performed by an engine drive into a gear box, as is well known. The scraper blade 30 and circle 31 are also capable of a side-shifting adjustment, usually performed by the energization of hydraulic rams or mechanical linkage in a well known manner, so as to enable either end of the scraper blade 30 to be projected out to a greater or lesser distance to each side of the frame 25. Moreover, the circle 31 can be tilted around a fore and aft axis extending substantially longitudinally of the grader, as by the energization of hydraulic rams or mechanical drive, in a well known manner, so that either side of the circle can be tilted upwardly or downwardly, whereby the corresponding end of the scraper blade can also be tilted upwardly or downwardly as desired. Still further, the entire assembly of the circle and blade can be raised and lowered to vary the cutting depth of the blade, and to swing the blade up to a raised inoperative position, as by the operation of the hydraulic rams or mechanical linkage, as is well known. In the later designs of motor graders, all of these blade positioning adjustments are effected in response to the operation of control levers or the like 36 located at the operator's position 37 on the motor grader.

These lifting, lowering, tilting and side shifting adjustments of the scraper blade 30 of the motor grader are utilized in effecting adjustments of the outer end of the strike-off blade of the shoulder spreading attachment unit AU', and will be described in greater detail later,

5 preliminary to the description of this shoulder spreading attachment unit. Both embodiments of attachment units AU and AU' have preferably been constructed and proportioned for use particularly in conjunction with six wheel motor graders having tandem pairs of rear driving wheels 27 and having front steering wheels 26 which may or may not be power driven, and the same or a comparable grader is illustrated in the drawings, but it will of course be understood that the invention is not limited to use with either of these specific graders.

10 Referring now to the main features forming the structural basis of both embodiments AU and AU', and with particular reference first to FIGURES 2, 3, 5, 6 and 7, it will be seen that the main frame thereof is of torque tube and box section design comprising at the rear a transversely extending horizontal tank tube 40 which constitutes the main back-bone of the frame. This tank tube 40 functions as an oil reservoir for storing a reserve quantity of oil for the hydraulic drive and hydraulic control system, and in this regard the large surface area of such tank tube functions effectively to dissipate the heat from the circulating oil. The ends of the tank tube 40 are closed by removable end heads 41, the removal of which affords access to the interior of the tank tube for cleaning the latter.

15 Welded to the underside of the tank tube 40 substantially at its center is the downwardly extending mounting bracket 43 having a spherical socket 44 formed in its underside. Secured to and projecting from the front end 20 of the motor grader MG is an upwardly extending ball 45 which is adapted to establish a ball-and-socket mounting joint within the spherical socket 44. A removable cap 46 having a spherical pocket in its upper surface is detachably secured by bolts or cap screws 47 to the underside of the mounting bracket 43. This ball and socket 25 mounting joint 44, 45, the details of which are best shown in FIGURES 20 and 21, constitutes the main draft transmitting connection between the motor grader MG and the attachment unit AU, and it will be seen that by the mere removal of the bolts or cap screws 47 this draft 30 transmitting connection can be easily separated for uncoupling the attachment unit from the motor grader. The shank of the mounting ball 45 is welded to a cross plate 49 which in turn has its ends welded to a pair of laterally spaced links 51 extending upwardly and rearwardly therefrom. The rear ends of these pivoting links 51 engage over opposite ends of a transversely extending boss 52 formed integral with the front end of the motor grader frame, and a transverse pivot pin 53 passes through the pivoting links 51 and boss 52. Welded to the underside 35 of the plate 49 and extending downwardly therefrom is a pair of laterally spaced arms 55 having a transversely extending plate 56 welded to their lower ends and projecting laterally beyond the arms. A U-shaped clevis 57 has its spaced ends passing through loose fitting holes in the projecting end portions of the plate 56, and nuts 58 screw over threads on the ends of the clevis. The clevis 57 embraces a curved arm or web 61 formed integral with the front end of the motor grader frame. By loosening the nuts 58 the clevis 57 may be shifted upwardly or downwardly along the curved arm 61 for raising or lowering the mounting height of the ball 45 with respect to the front end of the motor grader frame. If desired, an adjusting screw 62 may be threaded through a tapped hole 40 in the plate 56 between the spaced arms 55, by the adjustment of which screw the rear surface of plate 56 45 can be adjusted toward or away from the curved front surface of the arcuate web 61, thereby raising or lowering the height of the ball 45.

45 The frame of the attachment unit AU also comprises

left and right box channels 64 and 64' (FIGURES 5 and 6) which have their rear ends welded to the tank tube 40 and which slope downwardly and forwardly therefrom for welded attachment at their front ends to a transversely extending front frame tube 65. Welded to the front side of the frame tube 65 near the outer ends thereof, are two vertically disposed swivel brackets 66 in which vertical caster spindles 67 are journaled for castering rotation. Extending diagonally downwardly from each of the castering spindles 67 are caster arms 68 carrying transverse pivot pins or axles 69 on which one or more caster wheels 70 are mounted. The two laterally spaced caster wheel sets 70, 70 constitute two spaced points of support for the front end of the attachment unit frame, and the ball-and-socket mounting joint 44, 45 constitutes a third laterally rockable point of support for the rear end of the attachment unit frame. It will be evident that the ball-and-socket mounting joint 44, 45 permits independent transverse rocking movement between the motor grader MG and the attachment unit AU as the two vehicles pass over uneven road surfaces. I have found it preferable to use solid rubber tires on the caster wheels 70 so as to avoid the rise and fall of the strike-off blade level to which pneumatic tires are subject with different loads in the hopper. The solid rubber tires also enable single caster wheels to be used in many instances, as shown in FIGURE 4, instead of pairs.

Extending between the right hand side of each of the attachment units AU and AU' and a rearwardly disposed point of the motor grader MG is a pivotally acting stabilizer brace 72, which compels the attachment unit to steer directly with the front end of the motor grader (as permitted by the castering action of the wheels 70) and which also supplements the draft transmitting action of the ball-and-socket mounting joint 44, 45, while still permitting the aforesaid free transverse rocking movement between the attachment unit and the motor grader. As shown in FIGURE 7, this stabilizer brace 72 is preferably in the form of a long tube having a readily releasable ball-and-socket connection at its front end with the right hand end of the tank tube 40. This ball-and-socket connection comprises front and rear halves 74 and 75 of a spherical socket 76 adapted to engage over a ball 77 which projects upwardly from the right hand end of the tank tube 40. The rear socket half 75 is secured to the front end of the stabilizer tube 72, and the front socket half 74 is releasably secured to the rear socket half—over the ball 77—by two or more bolts or cap screws 78. This permits the ready disconnection of the stabilizer brace 72 when the attachment unit is to be uncoupled from the motor grader. The rear end of the stabilizer tube 72 has a vertically swinging pivotal connection or a ball-and-socket connection with the motor grader MG, as indicated at 79—81 in FIGURE 7. Referring again to the ball and socket mounting joint 44—45, it will be seen from FIGURES 1A, 1B and 3 that the single point axis of this ball and socket joint lies in the longitudinal central vertical plane passing through both the motor grader MG and the attachment unit AU or AU', as indicated by the dash-dot lines P—P in FIGURES 1A and 1B. This plane P—P passes midway in the tread spans of all four pairs of wheels, namely the two pairs of rear driving wheels 27—27 of the motor grader MG, the pair of front steering wheels 26—26 of the motor grader, and the front caster wheels 70—70 of the attachment unit AU or AU'. The freedom of the two vehicles MG and AU—AU' to have this relative transverse rocking movement is not hindered in any sense by the presence of the long diagonal stabilizing bar 72, the opposite ends of this stabilizer bar merely rising or falling relatively to each other in accommodating opposite directions of relative transverse rocking movement between the two vehicles. If desired, a duplicate stabilizing bar 72 may be arranged on the other side of the longitudinal plane P—P, comparable to a wish-bone relation, but I find that a single stabilizing bar is entirely

adequate. As previously described, this stabilizing bar compels the attachment unit to steer directly with the front end of the motor grader, as permitted by the castering action of the front attachment unit wheels 70; and the 5 stabilizing bar also supplements the draft transmitting action of the ball and socket mounting joint 44—45, while still permitting the aforesaid free transverse rocking movement between the two vehicles around a longitudinal axis lying in the central vertical plane P—P. Such freedom 10 of the two vehicles to have this relative transverse rocking movement therebetween results in the strike-off box 175 or the strike-off blade 275 (to be later described) being more accurately maintained at its respective predetermined height of strike-off of the filling material, irrespective of any pronounced undulations in the road surface encountered by the vehicle wheels 27, 26 or 70. For example, if the left hand rear traction wheels 27 of the motor grader MG should drop into a hole or depression along the left hand edge of the road, or should drop off this edge of the road, this would immediately tend to cock or twist the grader frame to bring the left hand side of the entire length of the frame down to a lower level than the right hand side. Let us assume that the attachment unit AU—AU' was coupled to the motor grader MG in 15 some such coupled relation that the free transverse rocking movement afforded by the transversely rockable joint 44—45 could not occur, then there would be a tendency to transmit the entire cocking or twisting of the grader frame to the frame of the attachment unit AU. This 20 could very well tend to depress the inner side or inner end of the laterally projecting strike-off box or strike-off blade through a substantial degree of downward movement below the predetermined set strike-off level, with the result that a substantially lesser depth of material 25 would be laid along this part of the road. This downward stressing of the strike-off side might be augmented at times by the overhanging weight of a long length of outwardly extending strike-off blade.

Now let us assume the present situation wherein the 30 two vehicle frames are connected together by the centrally aligned transversely rockable joint 44—45. In such a situation no part of the transverse cocking or twisting which is acting through the grader frame can be transmitted to the attachment unit frame. Also, only one-half 35 of the downward vertical component caused in the left hand side of the grade frame, by the left hand rear grader wheels dropping into a hole, will be transmitted as a downward component to the rear edge of the attachment unit 40 tending to swing this edge of the attachment unit downwardly around the front caster wheels 70—70. The transmission of this downward component from the grader frame to the attachment unit frame is reduced to one-half by reason of the fact that the transversely rockable joint 44—45 only transmits to the attachment unit frame one-half of the downward component occurring in the grader frame because the line of action of the transversely rockable joint 44—45 lies in the central plane P—P, which is exactly one-half or is midway of the distance between each pair of companion wheels. Thus, in the present instance under discussion, the attachment unit frame receives no twisting stress, and the inner side or inner end of the strike-off box or blade is only depressed one-half as far as in the other instance where there is no transversely rockable joint between the two vehicle frames. This would also be true in the reverse situation of the right hand rear traction wheels 27 dropping into a hole or depression on their side of the road.

It will also be seen from the foregoing that the above-described action of the transversely rockable joint 44—45 in 45 avoiding the transmission of twisting stresses from one vehicle to the other, also avoids the transmission of racking and twisting stresses from the frame of the attachment unit to the frame of the motor grader or other propelling vehicle. These racking, twisting stresses are 50 very likely to occur when this shoulder spreading or two

vehicle assembly is in transport, traveling at speeds ranging up to 20 miles per hour or more, and over considerable distances; or when the two vehicles are passing over bridges, around culverts, or driving over irregular ground. Also, these stresses are almost bound to occur when turning the two vehicle assembly around at the end of a shoulder-spreading run or pass along one edge of a road, possibly for making another shoulder-spreading run back in the opposite direction along the opposite side of the road, this operation of turning around almost inevitably occurring over some rough ground in view of the fact that the overall length of the shoulder spreading vehicle assembly is in the neighborhood of 30 feet. While the fore and aft axis of the single point transversely rockable ball-and-socket joint 44-45 preferably lies on the central longitudinal plane P-P of the two vehicles (FIGURES 1A, 1B), for obtaining the maximum benefits and advantages pointed out above, nevertheless this fore-and-aft axis of this transversely rockable joint 44-45 might not be centrally disposed on the central plane P-P, but might be offset therefrom toward either the right or left wheel lines of the two vehicles, possibly with some sacrifice of certain of the aforementioned benefits and advantages. The stabilizing bar 72 would continue to be used with any such offset location of the transversely rockable draft transmitting joint.

When the attachment unit AU or AU' is uncoupled from the motor grader by the separation of the ball-and-socket mounting joint 44, 45, and the disconnection of the stabilizer brace 72, the weight of the rear end of the attachment unit is brought to bear on a jack roller or wheel 82 which is lowered into engagement with the road surface for taking this weight of the rear end of the attachment unit AU or AU' off of the ball-and-socket mounting 44, 45 to facilitate disconnection of such mounting; and this rear roller 82 may also be employed to support the rear end of the attachment unit in a normal or raised position while the attachment unit is standing idle, disconnected from the motor grader MG. While these are the preferred utilities of this rear roller 82, it may also be employed to support substantially all or part of the weight of the rear end of the attachment unit AU or AU' while the latter is being propelled forwardly in the trench filling or shoulder spreading operation, as I shall presently describe. This jack roller 82 is pivoted at 83 between the side arms of a mounting clevis 84 which is secured to the rear end of a vertically swinging arm or yoke frame 85. The front end of the arm or yoke frame 85 has wide-axis mounting on a pivot pin or pins 86 supported in pivot lugs 87 projecting from the trench filler frame. Welded to the underside of the tank tube 40 and extending downwardly therefrom is a rigid jack leg 91 having a clevis shaped lower end 92 carrying a transverse pivot pin 93. Pivoted on the pin 93 is a pivot block 94 at the upper end of a piston rod 95 which extends downwardly into the cylinder 96 of a one way or single action hydraulic jack 97. Projecting from the lower end of the cylinder 96 is a pivot block 98 which is mounted on a transverse pivot pin 99 extending through the upper portion of the clevis 84. One or more return springs 100 are connected between the clevis 84 and the upper portion of the frame for normally holding the jack roller or wheel 82 elevated. When the attachment unit is in its coupled relation to the motor grader MG, with the mounting ball 45 seating in the mounting socket 44, the jack roller or wheel 82 may be held in an elevated position out of contact with the road surface by the action of the tension springs 100, unless it is desired that this rear roller 82 sustain part of the weight of the rear end of the attachment unit AU while the latter is in operation in a trench filling or in a shoulder spreading operation. When it is desired to uncouple the attachment unit AU or AU' from the motor grader, hydraulic pressure is caused to act in the hydraulic jack 97 for forcing the jack roller 82 downwardly against the road surface, thereby elevat-

ing the rear end of the attachment unit frame and enabling the mounting socket 44 to be easily lifted off of the mounting ball 45. The rear end of the attachment unit frame may be maintained in this elevated position by the hydraulic jack 97 during the entire time that it is uncoupled from the motor grader, or the rear end of the attachment unit frame may be lowered for resting on a suitable support other than the hydraulically maintained position of the jack roller 82. A small hand operated hydraulic pump 101 is mounted adjacent to the hydraulic jack 97 and is hydraulically connected therewith, so that the rear end of the attachment unit can be raised and lowered by the hand operation of the manually operated pump 101 and its conventional relief valve. When it is desired to have this roller 82 carry part or all of the weight of the rear end of the attachment unit AU during the trench filling or shoulder spreading operation, the hydraulic pump 101 is manually operated to force the roller down against the road surface with sufficient pressure to support any desired proportion of the weight of the rear end of the attachment unit AU, the hydraulic characteristics of the jack 97 locking the wheel 82 in this lowered rolling position. Because of the fact that it is only a single wheel and because of its location quite close to the fore and aft center line of the attachment unit AU, well between the front steering wheels 26-26 of the motor grader MG, it follows that this supporting roller or wheel 82 will track or follow sufficiently well during any of the steering movements of the motor grader and attachment unit, which are always on a large radius owing to the long wheel base of the combined vehicles.

Located between the transversely extending rear and front frame tubes 40 and 65 is a material receiving hopper 105 into which is dumped the hot or cold asphaltic mix, crushed rock, gravel or other material used in making the trench fill. This hopper comprises side walls 106, 106', a sloping rear wall 107, and a hydraulically operated vertically swinging dump apron or front hopper wall 108 (FIGURE 6) at the front edge of the hopper. This hydraulically operated dump apron or wall 108 comprises a transversely extending plate or wall 109 extending substantially from side wall to side wall of the hopper, and having a hinged rear edge which is pivotally mounted on a transversely extending pivot rod 111 secured to the frame. The front edge of the plate 109 is formed with an upwardly bent lip 112 to which is secured an upwardly extending section of pliable belting or webbing 113 adapted to strike the underside of the dump truck body. Projecting downwardly from the underside of the apron plate 109 substantially at its center are spaced pivot brackets or plates 115 carrying a pivot pin 116 therebetween, on which is pivoted an eye or clevis 117 secured to the upper end of a piston rod 118. This piston rod extends into a double acting hydraulic cylinder 119 which are pivotally connected at 120 at its lower end to the frame of the machine. This front hopper wall 108 normally occupies the relatively flat position shown in full lines in FIGURE 6. In the truck dumping operation, this front hopper wall 108 can, if desired, be swung upwardly by energizing the hydraulic ram 119 to bring the pliable upper edge 113 into engagement against the underside of the dumping truck body while the latter is tilting rearwardly in the performance of the dumping operation. In this manner, the fill material is prevented from spilling forwardly between the under side of the truck body and the hopper 105, irrespective of whether it is a high dump truck or a low one. After the dump truck has pulled away this front hopper wall 108 is given an upward tilting movement for dumping all of the material which has been dumped thereon by the truck, this material being carried up to an angle considerably beyond the angle of repose for discharge rearwardly toward the conveyor belt. It will thus be seen that the tilttable apron or wall 108, in its normal forwardly extending position, considerably increases the effective capacity of the hopper. Also, by virtue of the hydraulic cylinder operation of the tilttable

apron 108 it can be utilized to release or free sticky blacktop or like material which may tend to adhere within the body of the dump truck even after the truck body has been raised to its maximum angle of tilt. This load releasing operation is performed by suddenly admitting full hydraulic pressure to the ram 119 for causing the apron 108 to swing up with a quick motion so as to strike the underside of the tilted truck body with a sharp blow; or it may be performed by causing the apron to slowly lift the entire truck body when in its tilted position, and to then sharply drop the truck body to shake the load loose. Material adhering to the hydraulically operated apron 108 may also be shaken loose by quickly operating the hydraulic ram 119 in opposite directions, with the motion suddenly interrupted in each direction by the piston of the ram 119 striking the opposite ends of the ram cylinder, or the gate striking opposite end stops.

Rotatably mounted at the front edge of the machine are two horizontally disposed pusher rollers 122, 122, which are adapted to engage the rear wheels 123 of the dump truck for pushing the dump truck DT ahead of the attachment unit AU or AU' while the dump truck is dumping fill material into the hopper 105 during continuous forward movement of the attachment unit. These two rollers 122 are spaced apart a distance corresponding to the tread span of the rear wheels of the conventional dump truck. In regard to tread span, it should be noted that the tread span between the two caster wheel sets 70, 70 is substantially the same as the tread span of the motor grader wheels 26 and 27, thereby facilitating the loading of the attachment unit AU or AU' on to a heavy duty transport trailer and the detachment of the motor grader therefrom when it is desired to transport the attachment unit a substantial distance.

The rear hopper wall 107 and the hydraulically operated front hopper wall 108 discharge the material downwardly into a transversely extending feed channel 131 in the bottom of which travels a conveyor belt 132. Anchored along the front and rear side walls of the feed channel 131 are downwardly inclined deflecting plates 133, and secured to the undersides thereof are pliable sealing strips 134 composed of belting or rubber flashing material which establish sealing contact with the upper surface of the conveyor belt 132. The deflecting plates 133 and the self-cleaning pliable sealing strips 134 are tapered in width or have their edges extending in diverging relation in the direction of travel of the belt, so that they are self-relieving of fill material as the material is carried toward the discharge end of the belt at the left hand side of the machine.

As shown in FIGURE 3, the right hand end of the conveyor belt 132 passes around an adjustable idler roller 136 which is located at the right hand side of the machine. The shaft 137 of this idler roller is mounted at its ends in bearing blocks 138 which are capable of adjustable sliding travel along guideways 139. Adjusting screws 141 threading through yoke bars 142 effect sliding adjustment of the bearing blocks 138 for adjusting the tension on the conveyor belt 132. The top run of the belt carries a substantial part of the weight of the fill material in the hopper 105, and, accordingly, this top run is supported at closely spaced intervals by supporting rollers 144 carried by the frame and extending fore and aft directly below the top run of the belt. At its left hand end (FIGURE 3) the conveyor belt passes around a driving roller 147 which is also pivotally mounted in slidable bearing blocks 149, whereby the axis of this driving roller 147 may also be shifted inwardly or outwardly by the manipulation of adjusting screws 151, to provide proper belt alignment.

The left hand driving roller 147 is driven through suitable driving gearing (not shown) from a hydraulic motor 154, which is preferably a vane type of hydraulic motor. One such hydraulic motor which has proven satisfactory for the purpose is a relatively small high speed vane motor of well known make, which is connected

through a speed reducer of approximately a 20 to 1 ratio with the driving pulley 147. The hydraulic motor 154 is adapted to be driven from a hydraulic pump 157 which, in turn, is driven by a gasoline engine 158. One such hydraulic pump which has proven entirely satisfactory for the purpose is a well known gear pump having multiple pumping compartments. The internal combustion engine 158, hydraulic pump 157 and hydraulic motor 154 are extended in line along the rear edge of the machine, substantially entirely beneath the upwardly and rearwardly sloping rear hopper wall 107. However, in the use of certain designs of internal combustion engines, the projection of a part of the engine above the plane of this inclined rear hopper wall 107 may necessitate forming an upwardly bulged formation 107a in this rear hopper wall in the immediate vicinity of the engine.

The operator of the trench filling attachment unit AU sits on a transversely facing seat 161 which is located at the left hand side of the machine directly over the 20 trench to be filled and immediately adjacent to the large discharge opening 162 in the hopper side wall 106, through which the conveyor belt 132 discharges the fill material. The seat is mounted on a tubular bracket 163 projecting laterally from the side of the machine frame. 25 Directly in front of the operator's seat 161 are located controls 164—166, one of which controls in a continuously or uniformly graduated manner the flow of hydraulic pressure to the hydraulic motor 154. Thus, it is possible for the operator to regulate with infinitely 30 small speed changes the rate of discharge of the filling material from the discharge end of the conveyor belt 132, in order to take care of different depths and widths of fill and different operating conditions.

Referring to FIGURES 3 and 6, it will be seen that 35 there is provided a plurality of spaced clean-out holes 167 in the vertical front and rear walls 131 of the feed channel. These clean-out holes afford access to both edge portions of the top run of the conveyor belt 132 that project outwardly beyond the sealing strips 134, and 40 also to the top surface of the lower run of the belt. These clean-out holes are particularly useful for introducing live steam, furnace oil etc. for cleaning out encrustations of hot or cold asphaltic mix or other foreign matter; and also assist in discharging foreign matter in the normal running of the belt. To further aid in the 45 cleaning of the conveyor belt 132, it will be seen from FIGURE 3 that the bottom return run of the belt is caused to pass upwardly over a centrally located idler roller 168, thereby aiding in the gravitational discharge of dirt and other foreign material from the bottom run of the belt. Still further, it will be seen from FIGURES 3 and 8 that I have provided a unique design of floating inside belt scraper 169 adjacent to the tail pulley 136. This inside belt scraper is of V-shaped outline comprising spaced bars 170a and 170b bent to define sloping side wings 170, and having strips of pliable flashing material 170c clamped between the bars 170a and 170b. The lower edges of the pliable flashing material project below the bars for bearing against the top side of the return run of the belt. The V-shaped relationship of 55 wings 170 is pivotally connected at 171 to vertically swinging draft links 172 which are pivotally connected at their other ends to a pivot pin 173 carried by a stationary bracket 174 extending downwardly from the frame structure between the upper and lower runs of the belt. The pivoted linkage support of the V-shaped scraper 169 enables it to have floating movement so that it rides in direct gravitational contact against the top side of the return run of the belt, before this return run passes under the tail pulley 137. It will be obvious that 60 the V-shaped deflecting wings 170 will deflect dirt and other foreign matter in an outward direction from the top side of the return run of the belt. The above described features of the clean-out holes, sealing strips, V-shaped belt scraper, etc., are present in both attachment unit 65 embodiments AU and AU'.

Referring now more particularly to the trench filling embodiment AU, and to the manner of effecting the strike-off control of the material as it is discharged from the end of the conveyor belt down into the trench or shoulder area along the edge of the road, in one embodiment of the invention this is effected by a strike-off box 175 which is detachably mounted on the left hand side of the machine for vertical adjusting movement. Referring particularly to FIGURES 4 and 5, the strike-off box 175 is a two-sided structure which can be pivotally raised and lowered by the operation of a double acting hydraulic ram 176 for effecting different levels of strike-off of the fill material. The box can also be varied in width for obtaining different widths of fill. The box comprises a back wall 177 and an outer wall 178 which are adapted to be swung up and down together by the hydraulic ram 176 around the pivot axis x of a rotatable extension tube 180 that telescopes within the front frame tube 65. As shown in FIGURE 4, the extension tube 180 has a plurality of spaced arcuate slots 181 in its top surface, into which is projected a retractable latching pin 182 which is slidably mounted in a boss 183 carried by the frame tube 65. The withdrawal of the locking pin 182 permits the extension tube 180 to be slid inwardly or outwardly within the frame tube 65 for bringing any desired one of the arcuate slots 181 into registering position to receive the latching pin 182, depending upon the desired strike-off width of the box 175. The arcuate formation of each of the slots 181 permits the slight rotative movement of the extension tube 180 within the frame tube 65, which occurs when the strike-off level of the box 175 is raised or lowered.

The outer wall 178 of the strike-off box comprises a triangular plate 185 having its apex welded or otherwise secured to the extension tube 180. This wall plate 185 is supplemented by an outer triangular wall plate 186 which is pivoted in reverse relationship to the inner wall plate 185. That is to say, the outer wall plate 186 has a rearwardly extending apex which is pivoted to the inner wall plate 185 adjacent to the rear edge of the latter on a transverse pivot pin 187. Formed in the outer wall plate 186 adjacent to its swinging front edge is a long arcuate slot 188, and passing through this slot and through the lower edge of the inner wall plate 185 is a clamping bolt 189 which serves to clamp the outer wall plate to the inner wall plate in different angles of adjustment. A handle 191 secured to the upper portion of the outer wall plate 186 facilitates raising and lowering the outer wall plate 186 into these different angles of inclination, in which it is held by the clamping bolt 189. For example, when the strike-off box 175 is in a low position of adjustment for filling a deep trench T, as indicated in FIGURE 5, the outer wall plate 186 is also adjusted into a lower position, with its bottom edge 186' extending substantially horizontal and parallel with the bottom of the trench T. On the other hand, when the machine is traveling along the road in transport condition, or is only filling a relatively shallow trench T, with the inner wall plate 185 tilted up to an elevated position, the outer wall plate 186 is then likewise tilted up to an elevated position with the clamping bolt 189 tightened in a lower portion of the arcuate slot 188, thereby insuring that both wall plates occupy an elevated position.

The rear wall 177 of the box is secured to the rear vertical edge of the triangular wall plate 186. As shown in FIGURE 2, this rear wall 177 is made up of one or more vertically extending fabricated steel sections 177a, 177b, 177c, etc., which are adapted to be releasably secured together and to the triangular wall plate 186 by transverse bolts 193. The strike-off width of the box 175 can be increased or decreased by the addition or removal of successive rear wall sections 177c, 177d, etc.; and concurrently with the addition or removal of these sections the front extension tube 180 is shifted outwardly

or inwardly to bring different arcuate notches 181 into registration with the latching pin 182. The lower front edge of each wall section 177a, 177b, etc. is faced with a reenforcing or wear resisting bar 194 (FIGURE 5). 5 Projecting rearwardly from the back of one of the rear wall sections, such as the section 177c, is a pivot lug 195 carrying a pivot pin 196. Engaging over this pin is a clevis 197 at the lower end of the piston rod 198 of the double acting hydraulic ram 176. The cylinder 199 of this hydraulic ram has a clevis 201 at its upper end which is pivotally connected by pin 202 with a tongue 203 extending downwardly from the outer end of an overhead support tube 204. This support tube 204 extends horizontally across the top of the machine frame, where it passes through two spaced clamping brackets 205. Each of these clamping brackets has upwardly projecting yoke halves 206 which are adapted to be drawn together into rigid clamping engagement over the support tube 204 by the tightening of transverse clamping bolts 208. By releasing the clamping bolts 208, the support tube 204 can be slid inwardly or outwardly in order to maintain the double acting ram 199 substantially vertical as rear wall sections 177b—177d, etc. are added or removed to vary the strike-off width of the strike-off box 175.

Bolted or otherwise secured to the inner side of the innermost wall section 177a is a vertical movable guide plate 211 (FIGURE 5) which extends substantially the height of the wall section and which has its front edge 212 curved in the form of an arcuate concave guide surface, and which has its rear edge 213 curved in the form of an arcuate convex guide surface, both of which curved guide surfaces have the pivotal center x of the extension tube 180 as their center of curvature. The front concave arcuate guide surface 212 has sliding guided engagement with a stationary convex arcuate guide surface 214 of corresponding radius formed along the back edge of a stationary vertical guide plate 215 which is secured to the adjacent side of the machine. This stationary guide plate 215 has its bottom horizontal edge 215' terminating substantially at the hinged trench and curb seal 217, which will be presently described. The matching engagement of the two arcuate guide surfaces 212—214 in the different raised and lowered positions of the strike-off box 175 prevents any of the fill material from working inwardly across the face of the rear wall 177 and discharging beyond the inner edge of this rear wall.

Referring now to the rear convex guide surface 213 on the guide plate 211, the strike-off box 175 is laterally restrained against any inward or outward motion which would tend to laterally separate the arcuate guide surfaces 212—214, this lateral restraint being effected by the coaction between said rear convex guide surface 213 and a restraining roller 220 which rides on said guide surface (FIGURE 11). This restraining roller 220 has an outer annular flange 222 which overlaps the outer surface of the movable guide plate 211 along the convex rear guide surface 213. The restraining roller 220 is pivotally mounted on a pivot pin 223 projecting outwardly from a stationary mounting bar 224 which is secured to the frame of the machine directly on the inner side of the movable guide plate 211. This mounting bar 224 restrains inward shifting movement of the guide plate 211, and the outer confining flange 222 of the roller 220 restrains outward shifting movement of the movable guide plate 211, whereby inward or outward displacement of the strike-off box 175 is positively prevented. A reenforcing stationary strut bar 225 may extend between the mounting bar 224 and the machine frame.

Referring now to the hinged trench and curb seal 217, it will be seen from FIGURES 9 and 10 that this seal extends horizontally directly below the large discharge opening 162 through which the fill material is discharged from the conveyor belt 132. This seal 217 comprises 70 a long hinge leaf 230 having hinge eyes 231 in alignment

with stationary hinge eyes 232 secured to the machine, and through which aligned hinge eyes passes the hinge pin 233. Riveted or otherwise secured to this long hinge leaf 230 is an extending pliable flap 235 composed of belting, rubberized fabric or any other suitable pliable material. When the trench filler is in operation this hinged trench seal 217 is swung downwardly into the trench. It will be noted from FIGURE 5 that the rear end of the flap 235 extends to or overlies the matching arcuate guide surfaces 212-214 so as to close off the inner side of the strike-off box 175 at this point. When the machine is in operation, the flap 235 is swung down into the trench T so as to prevent the fill material from working inwardly over the curb edge of the trench T on to the surface of the road R. The hinged mounting of the curb seal 217 along its upper edge permits the lower pliable edge of the seal to swing either outwardly or inwardly, depending upon operating conditions, in either of which positions it serves to prevent the fill material from working inwardly over the top of the curb C. For example, if the machine should veer inwardly toward the right from the position shown in FIG. 10, this would bring the inner side of the curb seal 217 up against the upper edge of the curb C, causing the curb seal to swing outwardly at an angle around its upper hinged mounting, in which position, however, the curb seal 217 would continue to maintain pressure contact against the upper edge of the curb C so as to prevent fill material from working inwardly over the top of the curb C onto the surface of the road R. On the other hand, when the curb seal 217 is spaced from the edge of the curb C so that it tends to hang pendant from its overhead hinge mounting, it can only do so while no fill material is being discharged alongside the road. As soon as fill material starts to discharge, it begins to bank up against the outer side of the pendant curb seal 217, thereby swinging the lower edge of this seal inwardly into contact with the curb C, as indicated in dotted lines in FIGURE 10, in which position it also effectively prevents fill material from spreading inwardly over the top of the road. When the machine is to be placed in transport condition, this trench seal is swung upwardly to an elevated position above the road surface, in which position it is held by a chain 237 (FIGURE 9) which has one end secured to the hinged seal 217 and which is adapted to have its other end hooked to a stationary hook 238, for holding the hinged seal in an elevated inoperative position.

Extending across the bottom edge of the discharge slot 162 is a downwardly sloping wipe-off skirt 240 comprising an anchored confining bar 241 to the underside of which is secured a horizontally extending wipe-off strip 242 composed of belting, rubberized fabric or the like. The upper edge of this pliable wipe-off strip 242 bears resiliently against the outer surface of the conveyor belt 132 at the point where the belt is starting to pass down around the underside of the driving roller 147, whereby this pliable strip 242 tends to wipe off or remove any adhering particles of the filling material from the surface of the belt. The lower edge of this pliable strip 242 overlies the upper edge of the hinge leaf 230 of trench seal 217. As wear occurs at the upper edge of the wipe-off strip 242, from rubbing contact with the belt, the wipe-off strip can be adjusted inwardly. Screws 244 pass through the confining bar 241 and thread into flange 245 of sloping angle bar 246. This angle bar has bracket connection with a horizontal plate 247 mounted for inward and outward shifting adjustment on the support bar 248. Bolts 249 carried by the shiftable plate 247 pass through slots 251 in the support plate 248, and serve to lock the wipe-off skirt 240 in its different inwardly adjusted positions.

In FIGURES 1B and 14-19 inclusive, I have shown in detail the shoulder spreading embodiment of attachment unit AU', characterized particularly by the ability

to use a relatively long strike-off blade adapted to be set at a rearwardly inclined angle for more effectively distributing and spreading the fill material over a wide span. The rearwardly inclined angle of the strike-off blade also establishes an advantageous mixing action on bituminous mix which reduces segregation of coarse and fine materials. This modified construction is capable of placing and spreading material over a considerably greater span of trench or road shoulder—up to approximately 10 feet or more in width. One of the particularly unique features of this modified construction is the provision of an adjusting and thrust transmitting connection between the strike-off blade of the attachment unit AU' and the scraper blade 30 of the motor grader MG, whereby different operating adjustments of the attachment unit strike-off blade are effected through controlled movement of the motor grader scraper blade, and whereby the side thrust acting on the strike-off blade is transmitted to and borne by the scraper blade. Still further, the scraper blade can transmit an advantageous downward pressure to the strike-off blade.

Preliminary to the detailed description of the construction and mounting of this long strike-off blade on the unit AU', I shall first briefly describe certain of the conventional adjusting mechanisms provided as standard equipment on different motor graders for effecting the positional adjustments of the scraper blade 30, reference being made to FIGURES 12 and 13 which diagrammatically illustrate some of these conventional adjusting mechanisms. It will be seen therefrom that the circle 31 has rotative mounting on a goose-neck or A-frame 32 which sustains the draft of the scraper blade 30 through a ball and socket joint connection 33 with the front portion of the grader frame, this joint permitting universal movement of the rear end of the A-frame, together with the circle 31 and scraper blade 30 carried thereby. The operations of raising and lowering the A-frame 32, circle 31 and scraper blade 30 are performed through two forwardly extending control shafts 34 and 35 which have crank arms 34a and 35a on their front ends having universal joint pivotal connections with the upper ends of adjustable links 38 and 39. The lower ends of these downwardly extending links have universal joint pivotal connections at 38a and 39a with the outer ends of the transverse rear bar 32b of the A-frame 32. The rear ends of the left and right control shafts 34 and 35 enter housings 41 associated with a main control housing 41a at the operator's position 37. It is quite customary in these motor graders to have these two control shafts selectively driven in either direction by engine power through selective clutching operations performed in the housings in response to the manipulation of certain of the control levers 36 at the operator's position 37. Thus, if it is desired to raise or lower the scraper blade 30, with the latter remaining in the horizontal position or at a set angle, the selective rotation of the two control shafts 34 and 35 will swing their associated crank arms 34a and 35a either upwardly or downwardly to raise or lower the scraper blade as desired. As a secondary control manipulation, if it is desired to tilt the scraper blade, as for example to raise the left-hand end thereof (as viewed in FIGURE 13), either one or both of the two control shafts 34 and 35 may be rotated in a clockwise direction for transmitting a clockwise direction of tilt to the A-frame 32, circle 31, and blade 30 for tilting the left-hand end of the blade 30 in an upward direction.

Side shifting of the scraper blade 30 in either direction is adapted to be effected through a side shift rack 252 in the form of a sector gear 253 of relatively large radius which is suitably supported for rotative movement above the rear portions of the A-frame and circle. Meshing with this sector gear is a vertically disposed pinion 254 rotatively mounted below housing 255, into which enters a controllable drive shaft 256, the drive from shaft 256

being generally transmitted to the pinion 254 through worm gearing within the housing 255. The shaft 256 has operative connection with a reversible clutching drive at the operator's position 37 in response to the manipulation of one of the control levers 36. The lower rim of the sector gear 253 usually has one or more apertures 258 therein for selectively mounting a ball stud 259, which is adapted to establish a universal pivotal connection with the upper end of an adjustable link 260 extending diagonally downwardly to a universal pivotal connection 261 with one end of the A-frame cross bar 32b. By effecting the power driven rotation of the pinion 254 in either direction the sector gear 253 can be swung to right or left for imparting a corresponding swinging movement through the A-frame and circle to the scraper blade 30, such swinging motion occurring on the system of depending links 38 and 39. In this manner, either end of the scraper blade can be displaced outwardly to a substantial distance beyond the normal position of the scraper blade under the grader frame. The above described functions of raising and lowering the scraper blade, and of tilting it to different angles, performed through the crank arms 34a, 35a and the suspension links 38, 39, and likewise the function of side shifting the scraper blade through the rack 253 and pinion 254, are old, conventional controls which have been used on motor graders for years, as exemplified in Gustafson Patents No. 2,189,-286 and No. 2,258,890.

The range of outward displacement of the scraper blade 30 may be increased beyond that made possible by the side shift rack 253, as by providing a hydraulically operated blade offset mechanism 264 shown in FIGURE 13. In this arrangement, the scraper blade 30 is mounted for endwise sliding movement with respect to the curved supporting arms 31b extending downwardly from the circle 31. Extending horizontally through the lower ends of these curved arms 31b is a fixedly mounted guide tube 265. Mounted for sliding movement in the guide tube 265 is a guide rod 266 having its projecting ends anchored to the back of the scraper blade in anchoring lugs 266a. Adjacent to the upper edge of the scraper blade is another anchored guide rod 267 which has slideable movement within an upper guide tube 268. This upper guide tube 268 may have connection with the curved supporting arms 31 through any conventional blade tipping adjusting mechanism 269 (FIGURE 12) comprising serrated adjusting arms or members 269a attached to the ends of the upper guide tube 268, these adjusting arms 269a having corrugations 269b and slots 269c. Eye bolts 269d are fastened to the blade supporting arms 31b by nuts and lock washers, and each adjusting member 269a is adjustably fastened to eye bolt 269d by bolt 269e. This mechanism permits the upper edge of the scraper blade to be inclined forwardly or rearwardly with respect to the lower edge, without effecting the offset sliding adjustment of the blade endwise with respect to the blade supporting arms 31b. Such sliding offset adjustment of the blade is effected through a double acting hydraulic cylinder 270 disposed horizontally between the blade supporting arms 31b. Reciprocating in this cylinder is a reversably acting piston and piston rod 271. The anchored end of the cylinder 270 has a universally tiltable joint connection 270a with one of the curved supporting arms 31b, and the anchored outer end of the piston rod 271 also has a universally tiltable joint connection 271a with the back side of the scraper blade 30. Admission of hydraulic pressure to either end of the cylinder 270 is operative to effect the offset side shifting of the scraper blade in either direction relatively to the A-frame 32 and circle 31. Such offsetting adjustment of the scraper blade is old and well known, the above described hydraulically operated version being fully disclosed in Wilson et al. Patent No. 2,195,607 and in Leliter Patent No. 2,799,099; and a mechanically operated version thereof being disclosed in Antos Patent No. 2,183,058.

The mechanism for rotating the circle 31 relatively to the A-frame 32 is likewise old and well known. In one typical or conventional form it comprises a power driven pinion 272 which meshes with internal gear teeth 5 273 formed around the inner periphery of the circle 31 for rotating the circle in any of its raised, lowered, tilted or shifted positions, such circle rotating mechanism being typically illustrated in the aforesaid Gustafson Patents No. 2,189,286, and No. 2,258,890. In FIGURE 13 the 10 left-hand end of the scraper blade 30 is shown as having fastened thereto the adjusting and thrust transmitting connection which connects the scraper blade with the strike-off blade of the shoulder spreading embodiment AU'.

15 In this modified embodiment, the strike-off blade is designated 275, and is made up of fabricated steel sections 277a, 277b, 277c, etc., which may be identical to the rear wall sections 177a, 177b, etc. of the previously described strike-off box 175. Each of these sections is 20 preferably, although not necessarily, approximately one foot in width, and as many as 12 to 15 of these sections may be bolted together to provide a rearwardly inclined strike-off blade which will extend over an outer span of 10 feet or so. The other corresponding parts of this 25 modified construction bear the same reference numerals as are applied to the first described embodiment shown in FIGURES 1A, 2, 3 etc., with a prime suffix appended thereto. In this modified construction the attachment unit AU' is similarly supported at its front edge upon swiveling 30 caster wheels 70', and its rear edge is similarly supported on the front end of the motor grader MG through the separable ball and socket mounting joint 44', 45'; and the same relation of pivotally connected stabilizer bar 72' also extends between the attachment unit AU' and the motor grader MG.

35 Also, as shown in FIGURE 6A, this embodiment of attachment unit AU' likewise has the rearwardly disposed roller or wheel 82' operated by the hydraulic jack 97', comparable to the previously described wheel 40 82 and hydraulic jack 97, for raising the rear end of the attachment unit to facilitate the disconnection and reconnection of the ball and socket mounting joint 44', 45', and also to support any desired proportion of the weight of the rear end of the attachment unit AU' during the shoulder spreading operation. This rearwardly 45 extending support roller 82 or 82' can be given a vertical setting relatively to the road surface which will prevent or minimize variations of load in the hopper 105 or 105' of the attachment unit AU or AU' from causing variations in the depth setting of the strike-off box 175 of the trench filler, or of the strike-off blade 275 of the shoulder spreader. For example, the sudden dumping from a dump truck of a relatively large load of bituminous mix or other heavy material into the hopper 105, 50 105' places a greatly increased weight on the solid rubber tired front caster wheels 70, 70' of the attachment unit and on the pneumatic tired front steering wheels 26 of the motor grader MG. It is possible for the dumping of this large load of material into the hopper to cause 55 a substantial downward deflection of these rubber tired wheels, with a resulting change of setting of the strike-off box or strike-off blade. However, such downward deflection can be prevented or minimized by either setting the rear roller 82, 82' either for normal contact with the road surface, or in slightly spaced relation thereto 60 so that the roller will come down into immediate load bearing engagement with the road surface whenever a heavy load of material is dumped into the hopper of the attachment unit.

65 70 The inner end of this rearwardly inclined strike-off blade 275 has a two-way pivotal connection with the side of the attachment unit AU, which pivotal connection permits horizontal swinging movement of the strike-off blade about a vertical hinge axis, and also permits vertical swinging movement of the strike-off blade about a horizontal pivot axis. Referring particularly to FIG-

75

URES 14, 15 and 15A, it will be seen that the inner edge of the blade has bolted attachment to one leaf 281 of a vertically disposed hinge 280 which extends substantially the height of the blade. The other hinge leaf 282 has a horizontal pivot hole 283 therethrough for receiving a horizontal pivot bolt 284. This pivot bolt passes through a pivot hole 285 in a vertically extending attachment plate 286 of offset or Z-shaped section, the pivot bolt 284 passing through the oblique web portion 286a of this attachment plate. The forwardly extending leg 286b of this attachment plate is attached by rivets or bolts to a vertically reciprocable slide plate 287 which is mounted on the side of the attachment unit immediately in rear of the discharge opening 162 through which the fill material is discharged. A stationary frame plate 288 secured to the side of the attachment unit has a vertical guideway 290 formed on its outer surface in which the slide plate 287 has vertical sliding movement. This guideway 290 is made up of filler bars 291 defining the edges of the guideway, and outer confining bars 292 which confine the slide plate 287 in the guideway. The broad contacting surface areas of the hinge leaf 282 and web portion 286a, and the oblique angle of the web portion 286a, prevent binding of these parts under the twisting action of the strike-off blade 275. The rearwardly extending leg 286c of the attachment plate has a pivot lug 295 projecting from its lower end, and pivotally connected to this lug by pin 296 is the piston rod 297 of a substantially vertical double acting hydraulic ram 298. The cylinder 299 of this ram has its upper end pivoted at 301 to a pivot lug 302 which projects laterally from the end of the tank tube 40'. It will be seen from the foregoing that the strike-off blade 275 can be swung horizontally in an inward or outward direction around the vertical axis of the hinge 280, and can also be swung vertically about the horizontal axis of the pivot bolt 284. Furthermore, it will be seen that by energizing the double acting hydraulic ram 298 in either direction, the inner end of the strike-off blade 275 can be raised or lowered as desired, between an elevated position considerably above the surface of the road R or a depressed position in the bottom of the trench T. This is advantageous in performing multiple lift operations in which different levels of the fill material, or different fill materials, are laid in successive operations.

Referring now to the adjusting and thrust transmitting connection between the outer end of the strike-off blade 275 and the outer end of the scraper blade 30, this connection comprises a concave curved bolting fixture 305 which is secured by bolts 306 to the convex backside of the curved scraper blade 30, adjacent to the outer or left hand end of the blade. Projecting rearwardly and outwardly from this bolting fixture is an angular bracket 308 having vertically aligned widely spaced hinge eyes 309 through which passes a vertical hinge pin 310. Engaging over the upper and lower ends of these hinge eyes 309, and with the hinge pin 310 passing therethrough, are apertured pivot lugs 311 projecting from the ends of the vertical bar 312. Welded to this bar 312 is a horizontally extending strut or boom structure 315 comprising a horizontal main tube 316 and an inclined brace tube 317. The boom or strut 315 is made extensible by arranging an extension tube 318 for telescopic sliding movement within the horizontal main tube 316. The extension tube 318 is adapted to be held in any desired one of its different extended positions by a transverse locking pin 319 passing through the main tube 316 and receivable in any one of a series of holes 320 in the extension tube 318.

The outer end of the extension tube 318 has a ball-and-socket joint connection 322 with the outer portion of the strike-off blade 275. This connection 322 comprises a split spherical socket 323 carried by the extension tube and fitting down over a ball 324 projecting upwardly from a mounting bracket 325. This bracket 325 is adapted

to be detachably secured by the bolts 193 to one of the outer sections of the strike-off blade, such as to the section 277x which lies next to the outermost section 277y. Thus, the detachable bracket 325 can be bolted to the outer portion of any length of strike-off blade 275 (assembled from any desired number of sections 277a, 277b, etc.) that is required for the particular operating condition. It will be seen from the foregoing that the scraper blade 30 and its adjustable mounting on the motor grader MG, 10 together with the boom structure 315, jointly constitute an outer rear connecting mechanism between the motor grader MG and the outer rear end of the strike-off blade 275.

The outermost section 277y of the strike-off blade has 15 vertical hinge leaf connection 328 with the next inner section 277x, so that this outermost section 277y can be swung into a position extending substantially at right angles to the line of travel along the road R. Secured to the outer edge of this outermost section 277y is a margin defining plate 331 which extends forwardly from the section 277y for defining the outer margin of the filled surface or area. The margin plate 331 is adapted for vertical adjustment relatively to the blade section 277y, as by having bolts 193, which project horizontally from 25 the blade section 277y, pass through aligned vertical slots 332 in the rear edge of the margin plate 331. By the provision of this vertical adjustment, the margin plate 331 can be adjusted so as to have its substantially horizontal lower edge 331' lie somewhat below the lower 30 edge of the strike-off blade 275. Tiltably mounted at the forward edge of the margin defining plate 331 is a shoe plate 334 which has welded to its lower edge a flat sliding shoe 335 having an upwardly inclined front end 335'. This shoe plate 334 is mounted for vertical tilting 35 relatively to the margin plate 331, as by pivoting the lower rear corner of the shoe plate 334 to the margin plate 331 by a pivot bolt or pin 336. An arcuate slot 337 in the upper corner of the triangular shoe plate 334 has a bolt 338 passing therethrough, which bolt is carried 40 by the margin plate 331. The bolt 338 is tightened to hold the sliding shoe 335 at a predetermined angle. This sliding shoe carries some or all of the weight of the outer end of the strike-off blade 275, and can also function as a gauge for predetermining the closest approach 45 that the bottom edge of the strike-off blade can make to the working surface on which the fill is being applied.

As shown in FIGURE 19, an adjustable tie link connection 340 extends between the front face of the blade section 277x and the front edge of the margin defining plate 331. This connection comprises a U-shaped bracket 341 carried by the blade section 277x, into which is hooked the bent end 342 of a rod 343. The other end of this rod 343 is bent downwardly at 344 for engaging selectively in any one of a series of holes 345 in a link bar 346. The intermediate shank portion of the rod 343 may be arranged to pass very loosely through an enlarged hole 347 formed in the upturned end 348 of the link bar 346, so that the rod 343 and link bar 346 form a stiff leg in any of their positions of extensible adjustment. 50 The other end of the link bar 346 carries a pivot bolt 349 which is receivable in any one of a series of holes 351 formed along an inside flange 352 carried by the margin defining plate 331. This adjustable tie link 340 permits the shoe 335 and margin defining plate 331 to 55 be always pointed in the direction of travel, irrespective of the inward or outward angle which has been given to the strike-off blade 275 by the angular positioning of the scraper blade 30 in its rotative circle mounting 31, and also by the endwise side shifted positioning of the 60 scraper blade relatively to said circle mounting 31.

When the strike-off blade 275 is made up of a considerable number of blade sections, in order to extend the filling operation out to a very wide span, it may be desirable to stiffen the blade assembly against rearward bowing under the deflecting pressure of the fill material.

As shown in FIGURE 1B, this can be accomplished by extending strut bars 355 rearwardly from the central sections, and extending diagonal truss bars 356 from the end sections, and joining these strut bars and truss bars together by tie bolts 357.

In order to direct all of the fill material in a rearward direction toward the strike-off blade 275, I provide a vertically disposed, angularly adjustable deflecting wing 360 (FIGURE 1B) extending out from the side of the machine at a point directly forward of the front edge of the discharge opening 162. The inner edge of this deflecting wing has connection by a vertical hinge 361 with the side of the trench filling machine. The deflecting wing is adapted to be held in different angular positions by a locking pin 362 which has its inner end pivoted to a stationary clevis 364 and which has its outer downwardly bent end 365 receivable in any one of a series of holes 366 formed in a flange 367 projecting from the deflecting wing 360. When the attachment unit AU' is to be placed in transport condition for loading on a low bed trailer, the entire strike-off blade 275 can be readily removed from the machine. When the machine is to be moved through an obstructed area such as under a bridge or between high culverts, the strike-off blade can be folded back into a position approximately parallel with the length of the machine, as indicated in dotted lines in FIGURE 1B. The scraper blade also assumes this folded position while remaining connected to the strike-off blade, such being permitted by the inward telescopic shifting of the telescopic extension tube 318.

Summarizing the advantages of the strike-off blade 275 and its adjustments and mounting:

The rearwardly inclined angle and the considerable length of this blade effects a very desirable mixing of the fill material as it works backwardly along the blade, thereby minimizing segregation of the coarse and fine particles of the mix.

The separate vertical controls for the inner and outer ends of the strike-off blade, effected at the inner end by the hydraulic ram 298 and at the outer end by the scraper blade 30, enable the strike-off blade to be given any horizontal angle of slope desired.

The very large side draft resistance of the motor grader and its scraper blade 30 is made effective at the outer end of the strike-off blade 275 to sustain all of the very heavy side draft set up at the outer end of a long obliquely inclined strike-off blade.

The scraper blade 30 can transmit large lifting and lowering forces to the outer end of the strike-off blade. The ability of the scraper blade 30 to transmit heavy downward forces to the outer end of the strike-off blade is advantageous to prevent the outer end of the strike-off blade from climbing upwardly on or over the mass of fill material being distributed out across the inclined face of the strike-off blade—thereby maintaining a uniform level of fill.

The operative connection between the scraper blade and the outer end of the strike-off blade permits varying the width of the shoulder by varying the horizontal angle of the blade during the spreading or filling operation under power. This feature of being able to vary the horizontal angle of the strike-off blade quickly and easily also enables the operator to make changes in the blade angle to correct for flow distribution of the material across the face of the blade; i.e. if there is a tendency for a considerable part of the material to collect at the outer end of the blade against the divider plate 331 the operator can reduce the rearward angle of the blade, whereas if there is a tendency for not enough material to reach the outer end of the blade the operator can increase the rearward angle of the blade.

The ski type of shoe 335, by riding on the sub-grade ahead of the material being spread, serves as an accurate depth gauge for controlling the desired depth of fill.

The ability of the strike-off blade and the scraper blade

to be swung or folded rearwardly enables the transverse width of the entire assembly to be greatly reduced for passing through obstructed areas, such as under bridges, between high culverts, etc., in moving the assembly from one part of the road to another. In passing between ordinary culverts, the outer end of the strike-off blade can be tipped upwardly to a sharp angle for clearance and then returned to its operating position.

While I have illustrated and described what I regard to be the preferred embodiments of my invention, nevertheless it will be understood that such are merely exemplary and that numerous modifications and rearrangements may be made therein without departing from the essence of the invention.

I claim:

1. In combination, a motor grader comprising an adjustable scraper blade, a trench filling and shoulder spreading attachment unit comprising a frame, a pair of wheels supporting said attachment frame, a laterally rockable draft transmitting connection between the rear end of said attachment frame and said motor grader, a stabilizing bar pivotally connected between said attachment frame and said motor grader, a material receiving hopper carried by said attachment frame and adapted to receive fill material from dump trucks which are pushed ahead of the attachment unit in the truck dumping operation, a conveyor belt traveling in the lower portion of the hopper for discharging fill material from said hopper to the side of the attachment unit, a strike-off assembly comprising a strike-off blade and a dividing blade at the outer end of said strike-off blade, said strike-off blade having its inner end connected with said attachment unit at a point disposed rearwardly of and in relatively close proximity to the point of discharge of said conveyor belt and extending laterally and rearwardly therefrom at an angle, adjustable lifting and lowering mechanism connected between said attachment unit frame and the inner end of said strike-off blade for vertically adjusting the strike-off level of the inner portion of said blade, articulating means operatively connected between the inner portion of said strike-off blade and said attachment unit frame permitting substantially horizontal angulation and substantially vertical angulation of said strike-off blade relative to said attachment unit frame, said dividing blade limiting the outward distribution of the fill material along said strike-off blade to the margin defined by said dividing blade, a vertically adjustable gauging shoe supporting the outer portion of said strike-off assembly; and a boom pivotally connected at its inner end with said scraper blade and pivotally connected at its outer end with the outer portion of said strike-off assembly and operative to transmit inward and outward shifting movement and downward pressure from said scraper blade to the outer portion of said strike-off assembly.
2. In combination, a motor grader comprising an adjustable scraper blade, a shoulder spreading attachment unit coupled to the front end of said motor grader to be propelled thereby, said attachment unit comprising a material receiving hopper, a conveyor belt traveling in the lower portion of said hopper for receiving material from said hopper and discharging it laterally to one side of said attachment unit, a strike-off assembly comprising a strike-off blade and a dividing blade at the outer end of said strike-off blade, said strike-off blade having its inner end connected with said attachment unit at a point disposed rearwardly of and in close proximity to the point of discharge of said conveyor belt and extending laterally and rearwardly therefrom, said dividing blade being hingedly connected with the outer end of said strike-off blade and adapted to project ahead of said outer end in the direction of forward travel for limiting outward distribution of material along said strike-off blade to the margin defined by said dividing blade, an adjustable brace connected between said strike-off blade and said dividing blade for adjusting the directional angle of

said dividing blade, a ski type of gauge limiting shoe projecting forwardly from the outer portion of said strike-off assembly and adapted to ride on the sub-grade for predetermining the strike-off level of said strike-off blade, adjusting means enabling said shoe to be given different vertical angular adjustments relatively to said dividing blade, and a boom operatively connected between said scraper blade and said strike-off assembly.

3. In combination, a motor grader comprising an adjustable scraper blade, a shoulder spreading attachment unit comprising a frame, wheels supporting the front end of said frame, means for coupling the rear end of said frame to the front end of said motor grader to be propelled thereby, a material receiving hopper in said frame, a conveyor belt traveling in the bottom part of said hopper for receiving material from said hopper and discharging it laterally to the side of said attachment unit, a strike-off blade having its inner end connected with said attachment unit frame at a point in rear of and adjacent to the point of discharge of the fill material from said conveyor belt and extending outwardly and rearwardly therefrom for distributing the fill material by angular deflection, vertically adjustable lifting and lowering mechanism, carried by said attachment unit frame operative to vertically adjust the strike-off level of the inner end of said strike-off blade, articulating means operatively connected between the inner portion of said strike-off blade and said attachment unit frame, permitting substantially horizontal and vertical angulation of said strike-off blade relatively to said attachment unit frame, and a boom operatively connecting said scraper blade with the outer end of said strike-off blade and extending along the back side of said strike-off blade, whereby the side draft acting on said strike-off blade is borne as a compression stress in said boom, said boom transmitting rotative movement of said scraper blade around the axis of its circle to said strike-off blade, and also transmitting side-shifting movement of said scraper blade relatively to said motor grader to said strike-off blade, said boom comprising two extensible telescopic sections, means pivotally connecting one of said sections with said scraper blade, means pivotally connecting the other of said sections with said strike-off blade, and releasable means for locking said boom sections together in different extended positions.

4. In a shoulder spreading machine, the combination of a frame, wheels supporting said frame, a material receiving hopper carried by said frame, a transversely extending feed channel in the bottom of said hopper, a conveyor belt having its upper run traveling in said feed channel for conveying material from said hopper to the side of the machine, a driving roller and a tail roller at the ends of said feed channel over which said conveyor belt passes, a V-shaped belt scraper having diverging side wings riding on the upper surface of the return run of said belt in advance of said tail roller, pivoted link means anchoring said belt scraper whereby it is free to rise and fall gravitationally in contact with the surface of the belt, and clean-out holes in the side walls of said feed channel for affording cleaning access to the belt at different points along its length.

5. In combination, a motor grader comprising an adjustable scraper blade and means for raising, lowering and angularly adjusting said blade, a shoulder spreading attachment unit comprising a frame, wheels supporting said frame, a laterally rockable draft transmitting connection between the rear end of said attachment frame and said motor grader, a stabilizing bar pivotally connected between said attachment frame and said motor grader, a material receiving hopper carried by said attachment frame and adapted to receive fill material from dump trucks which are pushed ahead of the attachment unit in the truck dumping operation, a conveyor belt traveling adjacent to the bottom of said hopper for discharging fill material from said hopper to the side of the attachment unit, a strike-off blade having its inner end

connected with said attachment unit at a point disposed rearwardly of and in relatively close proximity to the point where said conveyor belt discharges the fill material and extending laterally and rearwardly therefrom at an angle, adjustable lifting and lowering mechanism connected between said attachment unit frame and the inner end of said strike-off blade for vertically adjusting the strike-off level of the inner portion of said blade, articulating means operatively connected between the inner portion

10 of said strike-off blade and said attachment unit frame and including vertical and horizontal pivot axes accommodating substantially horizontal angulation and substantially vertical angulation of said strike-off blade relatively to said attachment unit frame, a dividing plate angularly 15 adjustable on the outer end of said strike-off blade for defining the outer marginal edge of the fill, a gauging shoe operatively supporting the outer portion of said strike-off blade and said dividing plate and operative to slide on the ground so as to function as a gauge for predetermining 20 the closest approach between the outer portion of said strike-off blade and the working surface, and a boom pivotally connected on an upright pivot axis at its inner end with said scraper blade and pivotally connected at its outer end with the outer portion of said strike-off blade 25 and operative to transmit forward and rearward substantially horizontal swinging movement, and upward and downward substantially vertical raising and lowering movement from said scraper blade to the outer portion of said strike-off blade.

30 6. In a dual vehicle shoulder spreading assembly, the combination of a rear motor grader vehicle comprising a motor grader frame, front steering wheels and rear driving wheels supporting said grader frame, an adjustable scraper blade suspended from said grader frame between

35 said front and rear wheels, means for raising, lowering and angularly adjusting said blade, a front attachment vehicle coupled to the front end of said motor grader vehicle to be propelled forwardly thereby, said attachment vehicle comprising an attachment frame, laterally spaced wheels supporting said attachment frame, a transversely rockable draft transmitting joint connecting the front portion of said motor grader vehicle with the rear portion of said attachment vehicle, said transversely rockable joint lying in a vertical plane passing longitudinally

40 and substantially centrally through said rear propelling vehicle and through said attachment vehicle whereby both of said vehicles are free to have relative transverse rocking movement therebetween about the longitudinal axis of said joint, stabilizing bar means extending from said 45 motor grader vehicle to said attachment vehicle in laterally offset relation to said transversely rockable draft transmitting joint, pivot means pivotally connecting each end of said stabilizing bar means to its respective vehicle, whereby said stabilizing bar means operates to cause said

50 attachment vehicle to steer directly with the front end of said motor grader vehicle while permitting transversely rockable movement between said vehicles, a hopper carried by said attachment frame for receiving fill material dumped from dump trucks which travel ahead of said attachment vehicle, a conveyor traveling adjacent to the

55 bottom of said hopper for discharging the fill material from said hopper to one side of said attachment vehicle, a relatively long spreading and strike-off blade projecting outwardly from the side of said attachment vehicle at a point in rear of and in relatively close proximity to the rear edge of the point of discharge of said conveyor, said strike-off blade in its normal setting extending diagonally rearwardly at a relatively sharp angle whereby to effect a substantially uniform distribution of fill material out

60 along the entire length of the blade, and whereby to also effect a mixing of the fill material as it works outwardly and rearwardly along said blade so as to minimize segregation of the coarse and fine particles of the mix, adjustable lifting and lowering mechanism connected between the inner end of said strike-off blade and said at-

tachment vehicle for vertically adjusting the strike-off level of the inner portion of said blade, articulating mechanism connected between the inner end of said strike-off blade and said attachment vehicle comprising vertical and horizontal pivot means accommodating substantially horizontal angulation and substantially vertical angulation of said blade relative to said attachment vehicle, and a motion transmitting connection pivotally connected on an upright pivot axis at its inner end with the adjustable scraper blade of said motor grader vehicle and connected at its outer end with the outer portion of said strike-off blade and operative to effect horizontal and vertical angulation of said strike-off blade through manipulation of said scraper blade.

7. In a dual vehicle shoulder spreading assembly, the combination of a rear motor grader vehicle comprising a motor grader frame, steering wheels and driving wheels supporting said grader frame, an adjustable scraper blade movably mounted on said grader frame, means for raising, lowering, rotating and side-shifting said scraper blade relatively to said frame, a front attachment vehicle coupled to the front end of said motor grader vehicle to be propelled forwardly thereby, said attachment vehicle comprising an attachment frame, supporting wheels for said attachment frame, a transversely rockable draft transmitting joint connecting the front portion of said motor grader frame with the rear portion of said attachment vehicle frame, said transversely rockable draft transmitting joint having a transverse rocking axis lying in a fore and aft plane extending longitudinally of said two vehicles between the wheel lines thereof, whereby both of said vehicles are free to have relative transverse rocking movement therebetween about said fore and aft axis of the transversely rockable draft transmitting joint, stabilizing bar means extending from said motor grader vehicle to said attachment vehicle in laterally offset relation to said transversely rockable joint, articulating means establishing articulating connections between each end of said stabilizing bar means and its respective vehicle, whereby said stabilizing bar means causes said attachment vehicle to steer directly with the front end of said motor grader vehicle while permitting transverse rocking movement between said two vehicles, a hopper carried by said attachment vehicle frame for receiving fill material adapted to be dumped from dump trucks which travel ahead of said front attachment vehicle, a conveyor traveling in the lower portion of said hopper for discharging the fill material from said hopper to the side of said attachment vehicle, a relatively long strike-off blade projecting diagonally outwardly and rearwardly from said dual vehicle assembly at a point in rear of and in relatively close proximity to the point of discharge of said conveyor for receiving the fill material discharged by said conveyor and for spreading said material outwardly and striking it off at a predetermined level, said strike-off blade having its front inner end disposed in relatively close proximity to the rear end of said attachment vehicle in position to quickly start spreading and striking-off the fill material discharged by said conveyor, said strike-off blade in its normal setting extending rearwardly at a relatively sharp angle whereby to effect an intimate mixing of the fill material as it works outwardly and rearwardly along said blade so as to minimize segregation of the coarse and fine particles of the mix, first connecting means connecting one end portion of said strike-off blade with one of said vehicles and embodying adjustable lifting and lowering means for vertically adjusting the strike-off level of said one end portion of said strike-off blade, and second connecting means connecting the other end portion of said strike-off blade with the adjacent end portion of the motor grader scraper blade in a vertical motion transmitting relation whereby the strike-off level of said other end portion of said strike-off blade can be vertically adjusted by effecting corresponding vertical adjustment of the adjacent end portion of the motor grader scraper blade, the

connecting means at the inner end of said strike-off blade comprising substantially vertical axis pivot means accommodating substantially horizontal angulation of said blade relatively to said vehicle, and also comprising substantially horizontal axis pivot means accommodating substantially vertical angulation of said blade relatively to said vehicle, the connecting means connected with the outer end of said strike-off blade including a vertical pivot axis accommodating horizontal angulation of said strike-off blade for accommodating horizontal angular adjustment of said strike-off blade to different spreading angles inwardly or outwardly with respect to said dual vehicle assembly.

8. In a shoulder spreading vehicle comprising a motor grader unit and an attachment unit, said motor grader unit comprising a motor grader frame, steering wheels and driving wheels supporting said grader frame, an adjustable scraper blade movably mounted on said grader frame, means for raising, lowering, rotating and side-shifting said scraper blade relatively to said grader frame, said attachment unit being coupled to the front end of said motor grader unit to be propelled forwardly thereby, said attachment unit comprising an attachment frame, means supporting said attachment frame above ground level, a hopper carried by said attachment frame for receiving fill material dumped from dump trucks, a conveyor for discharging the fill material from said hopper to one side of said attachment unit, a strike-off blade projecting diagonally outwardly and rearwardly from said shoulder spreading vehicle for receiving the fill material discharged by said conveyor and for spreading such material outwardly and striking it off at a predetermined height, said strike-off blade having its front inner end disposed in relatively close proximity to the rear end of said attachment unit in position to quickly start spreading and striking-off the fill material discharged by said conveyor, first connecting means connecting one end portion of said strike-off blade with said shoulder spreading vehicle and embodying adjustable lifting and lowering means enabling the strike-off level of said one end portion of said strike-off blade to be adjusted vertically, and second connecting means connecting the other end portion of said strike-off blade with the adjacent end portion of the scraper blade of said motor grader in a vertical motion transmitting relation whereby the strike-off level of said other end portion of said strike-off blade can be vertically adjusted by effecting corresponding vertical adjustment of the adjacent end portion of the grader scraper blade, the connecting means at the front inner end of said strike-off blade including generally vertical and horizontal pivot axes accommodating vertical and horizontal angulation of said strike-off blade, the connecting means at the rear outer end of said strike-off blade including a vertical pivot axis accommodating horizontal angulation of said strike-off blade for accommodating horizontal angular adjustment of the strike-off blade to different spreading angles inwardly or outwardly with respect to said shoulder spreading vehicle.

9. In a shoulder spreading machine of the class described for spreading fill material alongside a roadway, said roadway having a substantially vertical curb along one edge thereof with a trench area extending outwardly from said curb, the combination of a frame, means for propelling said frame along said roadway, a material receiving hopper supported by said frame for receiving the fill material from dump trucks, a conveyor for discharging the fill material from said hopper outwardly into said trench area adjacent said curb, a spreading and strike-off blade extending diagonally outwardly and rearwardly from said frame rearwardly of said hopper for spreading and striking off the discharged material, and a curb seal carried by said frame below said conveyor for travel in said trench area, said curb seal comprising horizontal hinge means carried by said frame and extending longitudinally of the line of travel of said machine, and a down-

wardly extending pliable seal flap having hinged mounting on said hinge means and normally hanging downwardly therefrom in pendant position into said trench area adjacent said curb, said hinge means accommodating swinging movement of said seal flap laterally outwardly relative to said frame if the machine should move away from the curb and accommodating swinging movement of said seal flap laterally inwardly against the curb when the fill material banks up against the outer side of said flap, whereby said seal flap maintains contact with the curb for preventing the fill material from flowing inwardly beyond the curb onto said roadway.

10. In a road widening machine of the class described, the combination of a frame to be advanced forwardly along the road, a hopper carried at the forward end of said frame and extending transversely of said frame for receiving material from dump trucks which have tiltable dump bodies that dump over the forward edge portion of said hopper, horizontal hinge means extending transversely of said frame along the forward edge portion of said hopper, a dump apron hingedly mounted on said hinge means and extending forwardly therefrom, said apron normally extending forwardly from said hinge means in a substantially horizontal plane to accommodate passage thereover of the dump body of the truck, and extensible and contractable means operatively connected between said frame and the forward portion of said dump apron for moving the forward portion of said apron up and down, said extensible and retractable means being operable to swing the forward edge of said apron upwardly into engagement with the underside of the dump body during the truck dumping operation so as to prevent spilling of the dumped material in a forward direction between said hopper and the underside of said dump body.

11. In a shoulder spreading vehicle comprising a rear motor driven propelling unit and a front attachment unit adapted to be propelled forwardly thereby, said rear motor driven propelling unit comprising ground engaging driving means for driving said rear propelling unit, and an operator's position on said rear propelling unit embodying controls for steering said shoulder spreading vehicle and controlling the shoulder spreading operation, said rear motor driven propelling unit being heavier and having a greater length of wheel base than said front attachment unit and thereby having a greater capability of resisting the large side draft forces arising in shoulder spreading operations, pivotal coupling means pivotally coupling said rear propelling unit to said front attachment unit for permitting relative pivotal movement between the two units, said front attachment unit comprising an attachment frame, a hopper carried by said attachment frame for receiving fill material from dump trucks, front wheels for said attachment frame located forwardly of the bottom of said hopper so as to permit a relatively low disposition of said hopper for accommodating low dump trucks, a conveyor traveling in the lower portion of said hopper for discharging the fill material from said hopper to one side of said attachment unit, a relatively long spreading and a strike-off blade projecting diagonally outwardly and rearwardly from said shoulder spreading vehicle for receiving the fill material discharged by said conveyor and for spreading such material outwardly and striking it off at a predetermined height, said strike-off blade having its inner front end connected with said shoulder spreading vehicle at a point disposed rearwardly of and in relatively close proximity to the point of discharge of the fill material from said conveyor in position to quickly start spreading and striking off the fill material discharged by said conveyor, said strike-off blade in its normal setting extending diagonally outwardly and rearwardly at a relatively sharp angle approximately in the neighborhood of 45° whereby to enable the fill material to work itself out along the entire length of the blade with substantially uniform distribution, and

whereby to also effect a mixing of the fill material as it works itself outwardly along said blade so as to minimize segregation of the coarse and fine particles of the mix, inner front connecting mechanism pivotally connecting the inner front end of said strike-off blade with said shoulder spreading vehicle and comprising a substantially vertical axis pivot means accommodating substantially horizontal angulation of said blade relatively to said shoulder spreading vehicle and also comprising substantially horizontal axis pivot means accommodating substantially vertical angulation of said blade relatively to said vehicle, said inner front connecting mechanism also comprising adjustable lifting and lowering mechanism between the inner end of said strike-off blade and said shoulder spreading vehicle for vertically adjusting the strike-off level of the inner end of said strike-off blade, outer rear connecting mechanism pivotally connecting the outer rear portion of said strike-off blade with the rear motor driven unit of said shoulder spreading vehicle and including substantially vertical axis pivot means for accommodating substantially horizontal angulation of the outer end of said blade, said outer rear connecting mechanism comprising a side draft sustaining boom pivotally connected at its outer end with the outer portion of said strike-off blade and extending inwardly along the back side of said blade to a boom support on the rear propelling unit of said vehicle, whereby a substantial portion of the side draft exerted by said fill material against said strike-off blade is transmitted inwardly as a compression stress through said boom directly to said rear motor driven propelling unit of the shoulder spreading vehicle so as to utilize the greater side draft resisting capability of said rear propelling unit and without having to transmit such side draft through the pivotal coupling means connecting said front and rear units, a substantially vertical axis pivotal connection between said boom and boom support, means for rotating said boom support and boom to change the horizontal angularity of said strike-off blade, power operated lifting and lowering mechanism carried by said shoulder spreading vehicle and connecting with said boom support for raising and lowering the outer end of said boom and strike-off blade, and means enabling said power operated lifting and lowering mechanism to derive power from said shoulder spreading vehicle in response to the actuation of said controls at said operator's position for adjusting the strike-off level of the outer end of said strike-off blade during the continuous forward travel of said shoulder spreading vehicle.

12. In a shoulder spreading vehicle of the construction defined in claim 11 wherein the rear motor driven propelling unit has front steering wheels provided with pneumatic tires, the combination therewith of a ground engaging roller provided with a relatively hard tire surface thereon located substantially under the rear portion of said front attachment unit frame, and adjustable raising and lowering mechanism interposed between said ground engaging roller and the rear portion of said attachment unit frame for effecting relatively small graduations of vertical movement of said ground engaging roller relatively to said attachment unit frame, whereby said roller can travel slightly out of contact with the road surface when said hopper is empty or substantially empty of fill material, but which ground engaging roller will move down into load bearing engagement with the road surface when a dump truck dumps a heavy load of fill material into said hopper which would otherwise cause downward deflection of said pneumatic tires on the front steering wheels of the rear propelling unit, with resulting objectionable rise and fall of the strike-off blade with the dumping of successive loads of fill material into said hopper.

13. In a shoulder spreading vehicle comprising a rear motor driven propelling unit and a front attachment unit adapted to be propelled forwardly thereby, said rear motor driven propelling unit comprising ground engaging

driving means for driving said rear propelling unit, and an operator's position on said rear propelling unit embodying controls for steering said propelling unit and controlling the shoulder spreading operation, said rear motor driven propelling unit being heavier than said front attachment unit and having a greater capability of resisting the large side draft forces arising in shoulder spreading operations, coupling means coupling said rear propelling unit to said front attachment unit for permitting relative coupling movement between said two units, said front attachment unit comprising an attachment frame, means supporting said attachment frame above ground level, a hopper carried by said attachment frame for receiving fill material from dump trucks, a conveyor traveling in the lower portion of said hopper for discharging the fill material from said hopper to one side of said attachment unit, a relatively long spreading and strike-off blade projecting diagonally outwardly and rearwardly from the side of said shoulder spreading vehicle at a point disposed rearwardly of and in relatively close proximity to the point where said conveyor discharges the fill material to one side of said attachment unit, said strike-off blade in a normal setting extending diagonally outwardly and rearwardly at a relatively sharp angle to enable the fill material to work itself outwardly along the entire length of the blade with substantially uniform distribution, inner front connecting mechanism pivotally connecting the inner front end of said strike-off blade with said shoulder spreading vehicle and comprising substantially vertical axis pivot means accommodating substantially horizontal angulation of said strike-off blade relatively to said shoulder spreading vehicle and also comprising substantially horizontal axis pivot means accommodating substantially vertical angulation of said blade relatively to said vehicle, said inner front connecting mechanism also comprising adjustable lifting and lowering mechanism between the inner end of said strike-off blade and said shoulder spreading vehicle for vertically adjusting the strike-off level of the inner end of said strike-off blade, outer rear connecting mechanism pivotally connecting the outer rear portion of said strike-off blade with the rear motor driven unit of said shoulder spreading vehicle and including substantially vertical axis pivot means adjacent to the inner end of said outer rear connecting mechanism for accommodating substantially horizontal angulation of the outer end of said blade, said outer rear connecting mechanism having its outer end pivotally connected with the outer portion of said strike-off blade and extending inwardly along the back side of said blade to said vehicle, whereby the major portion of the side draft exerted by said fill material against said strike-off blade is transmitted inwardly as a compression stress through said outer rear connecting mechanism to said rear motor driven propelling unit so as to utilize the greater side draft resisting capability of said rear propelling unit and without having to transmit such side draft through said coupling means connecting the front and rear units, means for rotating said outer rear connecting mechanism to change the horizontal angularity of said strike-off blade, power operated lifting and lowering mechanism carried by said shoulder spreading vehicle and connecting with the outer portion of said strike-off blade for raising and lowering such outer portion, and means enabling said power operated lifting and lowering mechanism to derive power from said shoulder spreading vehicle in response to the actuation of said controls at said operator's position for adjusting the strike-off level of the outer end of said strike-off blade during the continuous forward travel of said shoulder spreading vehicle.

14. In a shoulder spreading vehicle comprising a motor grader unit and an attachment unit, said motor grader unit comprising a motor grader frame, steering wheels and driving wheels supporting said grader frame, said attachment unit comprising an attachment frame, ground engaging wheels supporting said attachment frame, piv-

otal coupling means pivotally coupling said attachment unit to the front end of said motor grader unit to be propelled forwardly thereby, stabilizing bar means pivotally connected between said motor grader unit and said attachment unit, a hopper carried by said attachment unit frame for receiving fill material dumped from dump trucks, a conveyor traveling in the lower portion of said hopper for discharging the fill material from said hopper to one side of said attachment unit, a strike-off blade projecting diagonally outwardly and rearwardly from said shoulder spreading vehicle for receiving the fill material discharged by said conveyor and for spreading such material outwardly and striking it off at a predetermined height, said strike-off blade having its front inner end disposed in rear of and in relatively close proximity to the point of discharge of the fill material, inner front connecting mechanism pivotally connecting the inner front end of said strike-off blade with said shoulder spreading vehicle and comprising a substantially vertical axis pivot means accommodating substantially horizontal angulation of said blade relatively to said shoulder spreading vehicle and also comprising substantially horizontal axis pivot means accommodating substantially vertical angulation of said blade relatively to said vehicle, said inner front connecting mechanism also comprising adjustable lifting and lowering mechanism between the inner end of said strike-off blade and said shoulder spreading vehicle for vertically adjusting the strike-off level of the inner end of said strike-off blade, said strike-off blade normally extending outwardly and rearwardly from said shoulder spreading vehicle at a rearwardly inclined angle which is capable of a substantial degree of horizontal angulation, outer rear connecting means connecting the outer rear end of said strike-off blade with said shoulder spreading vehicle, said outer rear connecting means comprising a boom support on the vehicle, means for tilting and rotating said boom support, and a boom pivotally connected on a vertical pivot axis to said boom support at one end and pivoted to the outer end of the blade at its other end for angularly adjusting or raising the outer end of said blade.

15. In a shoulder spreading vehicle comprising a rear motor driven propelling unit and a front attachment unit, said rear motor driven propelling unit comprising ground engaging driving means for driving said rear propelling unit, and an operator's position on said rear propelling unit embodying controls for steering said shoulder spreading vehicle and for controlling the shoulder spreading operation, said front attachment unit being coupled to said rear propelling unit to be propelled forwardly thereby, said front attachment unit comprising an attachment frame, means supporting said attachment frame above ground level, a hopper carried by said attachment frame for receiving fill material from dump trucks which travel ahead of said front attachment unit, a conveyor traveling in the lower portion of said hopper for discharging the fill material from said hopper to one side of said attachment unit, a relatively long strike-off blade projecting diagonally outwardly and rearwardly from said shoulder spreading vehicle for receiving the fill material discharged by said conveyor and for spreading such material outwardly and striking it off at a predetermined height, said strike-off blade having its inner front end connected with said shoulder spreading vehicle at a point disposed rearwardly of and in relatively close proximity to the point of discharge of the fill material from said conveyor in position to quickly start spreading and striking off the fill material discharged by said conveyor, said strike-off blade in its normal setting extending rearwardly at a relatively sharp angle whereby to effect a substantially uniform distribution of the fill material out along the entire length of the blade, and whereby to also effect an intimate mixing of the fill material as it works outwardly and rearwardly along said blade so as to minimize segregation of the coarse and fine particles of the fill material, inner front connecting mechanism pivotally con-

necting the inner front end of said strike-off blade with said shoulder spreading vehicle and comprising a substantially vertical axis pivot means accommodating substantially horizontal angulation of said blade relatively to said shoulder spreading vehicle, and also comprising substantially horizontal axis pivot means accommodating substantially vertical angulation of said blade relatively to said vehicle, said inner front connecting mechanism also comprising adjustable lifting and lowering mechanism between the inner front end of said strike-off blade and said shoulder spreading vehicle for vertically adjusting the strike-off level of the inner end of said strike-off blade, outer rear connecting mechanism pivotally connecting the outer rear portion of said strike-off blade with said shoulder spreading vehicle and including substantially vertical axis pivot means for accommodating substantially horizontal angulation of the outer end of said strike-off blade, said outer rear connecting mechanism comprising a side draft sustaining boom pivotally connected at its outer end with the outer portion of said strike-off blade and extending inwardly along the back side of said blade and pivotally connecting through said vertical axis pivot means to said shoulder spreading vehicle, whereby a substantial portion of the side draft exerted by said fill material being deflected outwardly along said strike-off blade is borne as a compression stress in said boom, said outer rear connecting mechanism comprising means for adjusting the horizontal angulation of said strike-off blade, and also comprising adjustable lifting and lowering mechanism carried by said shoulder spreading vehicle and connecting with the outer portion of said strike-off blade, said latter adjustable lifting and lowering mechanism being operable to adjust the strike-off level of the outer end of said strike-off blade.

16. In a shoulder spreading vehicle of the class described comprising a rear motor driven propelling unit and a front attachment unit, means supporting said front attachment unit above ground level, coupling means con-

necting said front and rear units permitting relative movement therebetween, a hopper carried by said front attachment unit and adapted to receive fill material from dump trucks which are pushed ahead of the front attachment unit, a conveyor belt traveling in the lower portion of the hopper for discharging fill material from said hopper to the side of the attachment unit, a strike-off blade extending diagonally rearwardly and outwardly from said shoulder spreading vehicle with the inner end of said blade disposed in rear of the point of discharge from said conveyor belt to receive the fill material therefrom inner and outer connecting mechanisms connecting the inner and outer ends of said strike-off blade with said vehicle and including lifting and lowering mechanisms for vertically adjusting the inner and outer ends of said strike-off blade and each including vertical axis pivot means for permitting horizontal angulation of said blade and including horizontal axis pivot means for permitting vertical angulation of said blade, means for adjusting the horizontal angularity of said strike-off blade, and stabilizing bar means pivotally connected between said front and rear units.
